UNITED STATES PATENT OFFICE

126,349

DESIGN FOR A PURSE

Harry Morris, Chicago, Ill.

Application March 10, 1941, Serial No. 99,480

Term of patent 3½ years

To all whom it may concern:

Be it known that I, Harry Morris, a citizen of the United States, residing in Chicago, in the county of Cook and State of Illinois, have invented a new, original, and ornamental Design for a Purse, of which the following is a specification, reference being had to the accompanying drawing, forming part thereof.

Fig. 1 is a side elevational view of a purse showing my new design.

Fig. 2 is a perspective view thereof, and Fig. 3 is an end elevational view thereof.

The other side and end of the purse are substantially like the side and end shown.

I claim:

The ornamental design for a purse, substantially as shown and described.

HARRY MORRIS.
